W. F. O'ROURKE,
CASEMENT ADJUSTER.

APPLICATION FILED NOV. 12, 1915.

1,198,144.

Patented Sept. 12, 1916.

UNITED STATES PATENT OFFICE.

WILLIAM F. O'ROURKE, OF CHICAGO, ILLINOIS.

CASEMENT-ADJUSTER.

1,198,144.

Specification of Letters Patent. Patented Sept. 12, 1916.

Application filed November 12, 1915. Serial No. 61,014.

To all whom it may concern:

Be it known that I, WILLIAM F. O'ROURKE, a citizen of the United States, and a resident of Chicago, county of Cook, and State of Illinois, have invented certain new and useful Improvements in Casement-Adjusters, of which the following is declared to be a full, clear, and exact description.

This invention relates to casement adjusters, and its principal objects are to increase the efficiency of casement adjusters; to eliminate the rattling of casements; to make a positive lock for the casement at any point of adjustment, and to simplify and otherwise improve upon the construction of devices of this class.

With these and other objects in view this invention consists in the several novel features hereinafter fully described and claimed.

The invention is clearly illustrated in the accompanying drawing, in which:—

Figure 1, is a view, partly in plan and partly in horizontal section, showing a simple embodiment of the present invention; Fig. 2, is a front view of the parts seen in Fig. 1; Fig. 3, is a detail, vertical section taken on line 3—3 Fig. 1; Fig. 4, is a detail section taken on line 4—4 Fig. 2, and Fig. 5, is a detail section taken on line 5—5 Fig. 1.

Referring to said drawing, the reference numeral 10, designates the frame, and 11, the casement window, hinged to said frame by hinges, one of which is seen at 12. For operating said casement 11, I employ an adjuster of novel construction, which will now be described. Secured in or on top of the window stool 13, is the base 14, of the adjuster, which is shown as secured to said stool 13, by screws 15. Conveniently said base may take an octagonal form having vertical sides 16, 17. A top piece or cover 18, is secured to said base by screws 19, 19^a; threaded in bosses 20, 20^a, formed on the base 14. Journaled in the vertical sides 16, 17, and extending therebetween is a worm screw, 21, which has a square end 22, projecting beyond the base and beyond the casement frame, to which squared end may be applied a crank 23, having a hub formed with a square socket for the reception of the squared end of the worm screw. Traveling upon said worm screw 21, is a nut 24, which is non rotative with respect to the worm screw, and has an upstanding pin 25, which travels in a slot 26, formed in an arm 27,

of a casement operating lever 28. Preferably a roller or sleeve 29, surrounds the pin 25, and bears against the edges of said slot. Said casement operating lever 28, is fulcrumed upon one of the screws 19, which fastens the cover to the base and the lever rests upon the boss in which said screw is threaded. The screws 19, 19^a, are disposed at the sides of said worm screw 21, and approximately midway between its ends to provide for right and left hand swinging casements. The lever 28, has a long arm 30, which extends lengthwise of the casement and its arm 27, is angularly disposed with respect thereto as shown in Fig. 1, so that its slotted end may travel the length of the worm screw.

The extreme end of the long arm 30, of the operating lever 28, is pivotally connected with a slide block 31, which is slidably mounted in a slotted tube 32, secured at its ends in brackets 33, fastened to the casement 11. Conveniently the slide block has outstanding ears 34, between which the end of the operating lever is pivotally secured, and it has also a cylindrical head portion 35, sliding in the hollow of the slotted tube 32.

In operation the crank 23, is applied to the squared end of the worm shaft 21, and turned in the proper direction, depending on whether the casement is to be opened or closed. In opening the casement, the rotation of the worm screw moves the nut forward, and the pin thereof slides forward in the slot of the operating lever arm 27, and swings the long arm of said lever backward and therewith the casement; the slide block 31, traveling or sliding back in the slotted tube 32. In closing the window the crank is turned in the reverse direction. It is to be noted that when the short arm 27, of the operating lever approaches the end of the closing movement of the lever, the slot in said arm extends at an angle to the worm screw; consequently a powerful action is had upon said arm by the worm screw and nut, since the upstanding pin on the nut, in traveling in said angularly disposed slot, has a sort of wedging action as well as a locking action, thereby positively and securely holding the casement in position free from any danger of rattling. By the use of the two upstanding bosses or lugs 20, 20^a, one on each side of the worm screw, the adjuster is capable of use for right and left hand swinging casements, by simply plac-

ing the operating lever on the proper lug or boss.

More or less variation of the exact details of construction shown and described, is possible without departing from the spirit of this invention; I desire, therefore, not to limit myself to the exact form of the invention shown and described, but intend in the following claims to point out all of the invention disclosed herein.

I claim as new and desire to secure by Letters Patent:—

1. A casement adjuster, comprising a base, a worm screw journaled therein, a nut traveling on said worm screw, a casement operating lever, having a long arm slidably connected with a casement, and a short arm angularly disposed with respect to said long arm and in sliding engagement with said nut.

2. A casement adjuster, comprising a base, a worm screw journaled therein, a nut traveling on said worm screw, a casement operating lever fulcrumed on said base and having a long arm slidably connected with said casement and a short arm angularly disposed with respect to said long arm, said nut having a pin projecting therefrom, traveling in a slot formed in the short arm of said lever.

3. A casement adjuster, comprising a

base, a worm screw journaled therein, a nut traveling on said worm screw, and having a lever actuating pin projecting therefrom, a pair of bosses, one projecting up from the base on either side of the worm screw and approximately midway between its ends, a casement operating lever arranged to be fulcrumed on either boss, and having a long arm slidably connected with a casement and a short arm angularly disposed with respect thereto, said short arm having a slot therein for the reception of the pin on the nut.

4. A casement adjuster, comprising a base, a worm screw therein, a casement operating lever fulcrumed on said base and operatively connected with said worm screw, a slotted tube secured to a casement and a slide block pivotally connected to said lever and sliding in said slotted tube.

5. A casement adjuster comprising a base, a worm screw rotatably mounted therein, a casement operating lever fulcrumed on said base, and having a long arm extending lengthwise of the casement and slidably connected therewith at its end, and having a short arm angularly disposed with respect to the long arm, a non-rotative nut traveling on said worm screw, and having a pin and slot connection with the short arm of said lever.

WILLIAM F. O'ROURKE.
